UNITED STATES PATENT OFFICE.

THOMAS D. WORRALL, OF WASHINGTON, DISTRICT OF COLUMBIA.

TYPE-WRITING MACHINE.

SPECIFICATION forming part of Letters Patent No. 366,750, dated July 19, 1887.

Application filed November 5, 1885. Serial No. 181,945. (No model.)

To all whom it may concern:

Be it known that I, THOMAS D. WORRALL, a citizen of the United States, residing at Washington, in the District of Columbia, have 5 invented certain new and useful Improvements in Type-Writing Machines, of which the following is a specification, reference being had therein to the accompanying drawings.

My invention relates to improvements in 10 type-writing machines, and especially to that class of machines in which fonts or batteries of type are arranged in a moving frame, as described and claimed in my Patent No. 334,503, of January 19, 1886.

15 Figure 1 is a top or plan view of my machine. Fig. 2 is a side view of the same, partly in section, taken on the line $x-x$ of Fig. 1. Fig. 3 is an end view of the type-carrying frame. Fig. 4 is a detached view of the centering-bar and a portion of the type-carrying frame. Fig. 5 is a side view of one of the adjustable arms for regulating the spacing of the letters. Fig. 6 is a side view of a portion of 20 the bottom of the main frame, showing the lower rod of the transverse frame passing therethrough.

25 Referring to the drawings, A is a rectangular frame, on the corners of which are secured the posts or brackets B, in which the rods or bars C and D are secured.

30 E is the type-carrying frame, the rear end of which is adapted to slide back and forth on the rod D to bring the proper letter to the printing point or center.

35 F is the type-carrying drum or cylinder, in which the type are arranged in rows in the periphery thereof. The type drum or cylinder is mounted in suitable bearings in the frame E, so that it can be readily turned to 40 bring the proper row of type in position to operate on the paper, said type-drum being provided with notches or recesses a' at one end to receive the sliding bolt G, which is secured to the frame E, so that when the type cylinder 45 is turned to bring the desired row of type into printing position it can be locked and securely held in such position. The front end of the type-carrying frame is provided with knobs or handles H, by means of which the frame 50 can be readily moved back and forth on the rod D.

I is a cross-bar, which constitutes a portion of the frame E, the lower edge of which is provided with notches b , adapted to fit over the projection K on the sleeve b' on the bar C, 55 said projection being situated at the printing point or center, to which each letter must be brought before the type-frame is depressed to form the letter or character, it being understood that the notches in the bar I are marked 60 with the same letters or characters as contained in the printing line of type in the cylinder, which lies directly behind it. The set-screws c are for the purpose of holding the sleeve b' on the bar C, so that said sleeve can 65 be accurately adjusted to bring the printing-center directly on the top and center of the paper-drum.

L are bars or brackets adjustably secured to the rear end of the type-frame by means of 70 thumb-screws, said brackets being connected together by a bar, M, which impinges on the pawl-operating mechanism to operate the same, as will more fully hereinafter appear.

N is a frame mounted transversely to the 75 frame A, and connected thereto by means of the rod a , which passes through the sides of the frame. The frame N consists of the end pieces, O and P, and the connecting-rods d .

R is a rod mounted in bearings d' , and rendered adjustable by means of screws e' in the ends O P, and on which is mounted the paper-holding cylinder S, the heads of said cylinder being provided with apertures through which the rod R is passed. The rod R is provided 80 with a left-hand screw-thread, e , into which a bolt, f , secured on the end of the cylinder, is forced by the spring f' , which causes the cylinder S to move rearward as it is turned by the pawl-plate, and when it is desired to move 85 the paper-cylinder forward for the purpose of putting on a new sheet of paper the spring-bolt is raised and the paper-cylinder drawn forward. The paper-cylinder is provided with a slot, T, in which the ends of the paper 90 are secured by means of a beveled strip fitting in said slot over the paper in the usual manner.

U is a ratchet-disk secured to the rear end of the paper-cylinder S, which is engaged by 100 the pawl-plate V to turn the paper-cylinder the proper distance to space between the let-

ters. The teeth of a portion of the ratchet-disk U opposite the end of the slot T are cut away, as shown at g, Fig. 2, so that when the paper-cylinder has reached that point in its revolution and the end of the line of printing has been reached the pawl-plate will drop into the recess g, causing the pawl-plate to strike the hammer i and ring the bell k to warn the operator that the end of the line of printing has been reached. When the pawl-plate drops into the recess g, it ceases to act on the paper-cylinder until said cylinder is moved over the slot to commence a new line of printing, which is done by turning the cylinder so as to bring the pawl-plate into contact with the ratchet-teeth of the disk again.

The pawl-plate V is made of the same length as the paper-cylinder, so that it will operate at all times on the ratchet-teeth of the disk U, no matter in what position the paper-cylinder is on the rod R.

The pawl-plate V is pivoted upon a rod, W', connecting the two side arms of the pivoted frame W, said frame being pivoted upon one of the rods d and held in normal position by the spring h, attached at one end to the bed-frame, and at the other to a stay-rod, W², of the frame W. At W² is shown an aperture for another stay-rod, and the upper ends of the side pieces of the frame W are connected by still another rod, l, which lies immediately beneath the bar M of the type-carrying frame, so that when the front of said frame is lifted the bar l is pressed down, rocking the frame W against the stress of spring h and causing the pawl-plate to positively turn the paper-cylinder. When the bar M rises, frame W is rocked upward by its spring h and the pawl-plate drops back one or more teeth of the ratchet-wheel.

As before stated, the bars L, which support the cross-bar M, are made adjustable on the type-carrying frame, so that said bar M can be moved toward or from the type-carrying frame, and in this manner adjust the throw of the swinging frame carrying the pawl-plate to regulate or determine the spacing. It will be seen that if the bar M be moved farther from the pivotal point of the type-carrying frame the swinging frame W will be forced down farther by the upward movement of the front end of the type-carrying frame than if the bar M were nearer to the pivotal point of the type-frame, and thus move the paper-cylinder around to space the distance between the large letters. When spacing for small letters, the bar M is moved forward toward the bar D, or pivotal point of the type-carrying frame.

As a further means of limiting the movement of the swinging frame W, and the consequent movement of the pawl-plate over the ratchet teeth of the disk U, I pivot one end of the bar A' to the top of the end P of the transverse frame N, the other end of said bar being provided with a slot, m, through which the bar l of the swinging frame W passes. The

bar A' is provided with a series of holes, n, which pass through the slot m, said holes being adapted to receive the thumb-screw v, and if wide spacing is required the set-screw is entirely removed or placed in the hole farthest from the bar l; but if spacing for narrow letters is required the thumb-screw is moved over toward the bar l and inserted in the hole, n, nearest the bar l, and by thus limiting the motion of the frame W, I am enabled to accurately space between the letters.

As a still further means of limiting the throw of the type-carrying frame to space the distance between the letters, I join the front end of the type-carrying frame to the sliding standard B' by means of a sliding connection, which consists of a T-headed projection or hook, r, passing through a slot in said standard, which will allow the front end of the type-carrying frame to be raised and lowered, the throw of said frame being limited by the adjustable pin p. The lower end of the standard B' is provided with a hole, which adapts it to slide back and forth with the type-frame on the rod C.

D' are troughs or strips, of wood or suitable material, secured at one end to suitable supports on each side of the paper-drum, while the outer ends of said troughs are secured to the ends of the rectangular frame A.

The bars D' are designed to support the inking ribbons or pad E', so that when the type-drum is moved back and forth in the processes of writing the type will be supplied at all times with a suitable amount of ink, and when fresh surfaces of the inking-ribbon are required it may be moved forward by winding or unwinding from the drums or spools F'.

Having thus described my invention, what I claim, and desire to secure by Letters Patent, is—

1. In combination with the traveling paper-cylinder and its ratchet-wheel, the elongated pawl-plate V, constructed and arranged, as described, to operate on the paper-cylinder throughout its travel.

2. In a type-writing machine, the pawl-plate V, constructed as described, mounted in the swinging and spring-held frame W, in combination with the type-carrying frame E, provided with the adjustable bar M, and the paper-cylinder having the ratchet-disk U, as set forth.

3. In a type-writing machine, the pawl-carrying frame W, in combination with the slotted bar A', having the holes n and set-screw v, as and for the purpose set forth.

4. In a type-writing machine, the paper drum or cylinder S, having the ratchet-disk U, provided with the recess g, in combination with the pawl-plate V, hammer i, and gong k, as set forth.

5. The combination of the sliding frame, the type-drum journaled in said frame and having longitudinal rows or alphabets of type

and recesses corresponding to the rows, and the sliding bolt mounted on the frame, as set forth.

6. The combination, with the type-cylinder and its pivoted frame, having the notched bar K, of the adjustable guide-block b', as set forth.

7. The combination, with the pivoted type-carrier having adjustable arms L and bar M, of the paper-roller, its ratchet-wheel, and the elongated pawl-plate, as set forth.

8. The combination of the sliding frame, the type-cylinder journaled in said frame and having longitudinal rows or alphabets of type

and recesses corresponding to the rows, and the sliding bolt mounted on one of the side bars of the frame, as set forth.

9. The combination, with the paper-roller and its ratchet-wheel, of the elongated pawl-plate, the pivoted type-carrier, and the bar M, mounted on adjustable arms L, as set forth.

In testimony whereof I affix my signature in presence of two witnesses.

THOS. D. WORRALL.
